UNITED STATES PATENT OFFICE.

JOHN P. McCARTY AND FRITZ W. FALCK, OF LOS ANGELES, CALIFORNIA, ASSIGNEES TO
PNEUMATIC SURF FISH COMPANY, OF SAN FRANCISCO, CALIFORNIA, A CORPORA-
TION OF CALIFORNIA.

DESIGN FOR A SURF-RIDER.

54,109.

Specification for Design.

Patented Nov. 4, 1919.

Application filed May 9, 1918. Serial No. 233,574. Term of patent 3½ years.

To all whom it may concern:

Be it known that we, JOHN P. McCARTY and FRITZ W. FALCK, both citizens of the United States, residing at Los Angeles, in the county of Los Angeles and State of California, have jointly invented a new, original, and ornamental Design for Surf-Riders, of which the following is a specification, reference being had to the accompanying drawing, forming part hereof.

In the drawing,

Figure 1 is a top plan view showing our new design for surf riders; and

Fig. 2 is a side elevation of the same.
We claim:

The ornamental design for a surf rider, as shown.

JOHN P. McCARTY.
FRITZ W. FALCK.
